UNITED STATES PATENT OFFICE.

ROBERT W. HARE, OF ALLEGHENY, PENNSYLVANIA, ASSIGNOR TO
D. DALLAS HARE, OF SAME PLACE.

ELEVATOR.

SPECIFICATION forming part of Letters Patent No. 596,589, dated January 4, 1898.

Application filed March 20, 1895. Serial No. 542,480. (No model.)

To all whom it may concern:

Be it known that I, ROBERT W. HARE, a citizen of the United States of America, residing at Allegheny, in the county of Allegheny and State of Pennsylvania, have invented certain new and useful Improvements in Elevators, of which the following is a specification, reference being had therein to the accompanying drawings.

10 This invention relates to certain new and useful improvements in elevators, and more particularly to that class of inventions known as "fire-doors for elevator-shafts."

The invention has for its object the provision of novel means whereby the fire-doors may be carried on the top of the elevator-car, as well as below the same, closing the hatchway automatically as the car ascends and descends; furthermore, to securely lock the 20 doors to their respective floors, thereby providing a safeguard that will be obviously apparent.

A further object of my invention is to construct elevator-doors of the above-referred-to 25 class that will be strong, durable, comparatively inexpensive to manufacture, and efficient in their operations; furthermore, to so construct the doors or hatch-guards that when the latter are placed in position less draft will 30 be created than with the guards employed at the present day.

A still further object of the invention is to dispense with the hangers at the top of the elevator-shaft and provide a novel mechanism 35 on the lowermost door whereby the series of doors or guards may be retained at any desired floor.

With the above and other objects in view the invention finally consists in the novel 40 construction, combination, and arrangement of parts to be hereinafter more particularly described, and specifically pointed out in the claims.

In describing the invention in detail reference is had to the accompanying drawings, 45 forming a part of this specification, and wherein like letters of reference indicate similar parts throughout the several views, in which—

Figure 1 is a view in perspective of an elevator. Fig. 2 is a view in elevation looking at

its front. Fig. 3 is a top plan view thereof. Fig. 4 is a plan view of the bottom of the lower door of the top series. Fig. 5 is a view in perspective of a section of the side posts, showing the weights and connections. Figs. 6 and 55 7 are views showing the gravity-latch and a modification, respectively.

In the drawings, A denotes the elevator-car, provided at its top with door-supports A' A', which may be of any desired construction 60 or form.

A² A² denote guides arranged at the sides of the elevator-car and adapted to partially embrace the side posts B of the elevator-shaft.

C denotes the lowermost door of the top series, arranged directly above the elevator-car, 65 provided with a gravity-lever C', slightly weighted at its free end C², and notched, as shown at C³, said lever being suitably hinged at C⁴. An operating-lever C⁵ is attached at 70 its free end to a line C⁶ and fulcrumed at C⁷ near the center of the door. Near the center of said lever is attached a link C⁸, connected to a pivoted arm C⁹, the latter being pivoted at C¹⁰ and provided at its free end with a slot C¹¹, be- 75 ing designed to engage a pin C¹² of the bolt C¹³, said bolt operating in a guide C¹⁴. The pivoted arm C⁹ also carries a link C¹⁵, and to the latter is attached an arm C¹⁶, centrally pivoted at C¹⁷, engaging a pin C¹⁸ of the bolt C¹⁹, op- 80 erating in a guide C²⁰. The end of the operating-lever C⁵ carries a link C²¹, and attached thereto is a pivoted arm C²², pivoted at C²³ and apertured at C²⁴ for the reception of the pin of the bolt C²⁵, operating in a guide C²⁶. 85 Attached to the pivoted arm C²² is a link C²⁷, connected to a pivoted arm C²⁸, centrally pivoted at C²⁹ and provided with an aperture for the reception of the pin of the bolt C³⁰, operating in a guide C³¹. Attached to the pivoted arm C²⁸ is a link C³², connected to a pivoted arm C³³, centrally pivoted at C³⁴ and provided with an aperture for the reception of the pin of the bolt C³⁵, operating in a guide C³⁶. Bearings C³⁷ are 90 also arranged on the under side of the door, and in the latter is journaled the pulley C³⁸.

C⁴⁰ represents a weight attached to the line C⁶.

The reference-letter D denotes a gravity- 95 pawl forming a latch arranged at each side of a landing or floor. Said pawl is apertured at D' for the reception of a pivot, the said pawl being of peculiar construction, provided with an inclined bearing-surface D⁸ above the 100

recess D⁴ and an inclined bearing-surface D⁵ below the recess D⁴. The top of said pawl is slightly weighted at D⁶, for purposes to be hereinafter more particularly described. The recess D⁴ shown in Figs. 6 and 7 of the drawings is beveled at D⁷, showing a modified form of the pawl, as illustrated in Fig. 7 of the drawings.

E represents the covering at the top of the elevator-shaft, having arranged thereon horizontal pulleys E', E², E³, and E⁴. The pulleys E⁵ E⁶ E⁷ E⁸ E⁹ E¹⁰ E¹¹ E¹² are arranged on a common shaft E¹³, and on the opposite side of the covering E are the pulleys E¹⁴ E¹⁵, on a common shaft E¹⁶, and on the same side are arranged the pulleys E¹⁷ E¹⁸, and directly in alinement with the same are the pulleys E¹⁹ and E²⁰.

The reference-letter H represents a counterbalance - weight which is suspended by means of cables or lines F' F² F³ F⁴, the said lines F' and F² passing over pulleys E⁵ and E⁶, respectively, and connecting with the uppermost of the lower doors—i. e., door E²¹—beneath the elevator-cage. F⁴, being attached to the weight H, passes over the pulleys E¹¹ E² E' E²⁰, and thence to the lower door E²¹, arranged underneath the elevator - carriage. The line F³ is also attached to the weight H, passing over the pulleys E¹², E², E', and E¹⁸, and thence to the door.

It will be noted that the pulleys E', E², E³, and E⁴ are double pulleys, one arranged above the other, and may be operated in opposite directions.

H' represents the lower weight, having connected thereto lines G', G², G³, and G⁴. The said lines G' and G³ pass over pulleys E⁷ and E⁸, respectively, the line G' passing over to the pulley E¹⁵, and thence to the second door G²¹, arranged under the elevator-car. The line G² is also passed, as heretofore stated, over the pulley E⁸, and thence to the second door G²¹ under the elevator-car, the lines G³ and G⁴ passing over pulleys E⁹ and E¹⁰, respectively, the line G³ passing over the pulleys E⁴ E³ E¹⁷ to the door G²¹, as heretofore stated. The line G⁴ passes over the pulley E⁴, E³, and E¹⁹, and thence to the door G²¹. The counterbalance - weights are apertured, as shown at H², and slotted at the sides at H⁴, forming guides against the side posts. The said apertures are diminished as the lower weights are reached, as a less number of lines are required to pass through the same. The weights are beveled at the sides, as shown at H⁵. Stops or rests are provided on the side posts, as illustrated by reference-letters H⁶ H⁶.

I represents the door-supports arranged at the top of the elevator-shaft, which are preferably bent at right angles, as shown at I' I'.

The operation of the device is as follows: For the purpose of illustration let us assume that the elevator-car is in the position as shown in Fig. 1 of the drawings. As the car ascends in the elevator-shaft the door-supports arranged at the top of the elevator-car

will engage the door next above it, the same being released by the gravity-latch being thrown out of alinement, the car engaging the inclined bearing-surface and thereby producing the desired result. The same operation will take place at the floor above, and so on consecutively until all or the desired number of doors are released from the gravity-pawls and stored at the top of the elevator-shaft. In order to store the doors, the line C⁶ is operated, thus communicating motion to the lever C⁵, thus operating the series of pivoted arms and links, as shown in dotted lines, Fig. 4 of the drawings, causing the bolts to be forced outwardly beyond the line of the doors and engaging the door-supports I at the top of the shaft. Simultaneously with this operation, as the lever C⁵ is drawn over to the desired position, the gravity-lever C' will engage the latter by reason of the slot or notch C⁸ engaging said operating-lever C⁵ and locking the same in this position. In order to release the doors from their holders, the door-supports on the car are so arranged as to come in contact with the weighted end of the gravity-lever C'. The latter, being hinged, will be slightly lifted and disengage the operating-lever C⁵, the latter then assuming its normal position by reason of the weight attached to the line C⁶, said line in turn being connected to the lever C⁵, the above operation causes the bolts to contract and release the doors from their supports, thus allowing the doors to pass down and engage at their respective floors or landings. It will be understood that the old and well-known system of graduated blocks or stops is employed to accomplish the above purpose. As the elevator-car ascends from the lower floor the counterbalance-weights operating the lower doors will travel downwardly to their respective stops, and when this point is reached the lower doors will have reached their respective floors and also engage the gravity pawl or lock. As the car again descends the inclined surface of the gravity-pawl will be engaged, causing the doors to be released and forced downwardly as the car descends, the weights by this operation being taken from their supports and carried upwardly. It will be noted that a great advantage is obtained by reason of the arrangement of the stops provided for the weight, as the doors arranged below the elevator-car are not required to be cut out to pass the stops, which would be otherwise required. By this construction less draft is created and a more efficient set of doors is produced.

It will be readily seen that the doors arranged below the elevator-car may be dispensed with, if desired. I direct particular attention to the gravity pawl or latch, the latter releasing the doors by reason of being forced out of alinement as the car ascends and descends, engaging the inclined bearing-surface. If it is desired to securely lock the door, the gravity-pawl as shown in Fig. 6 of

- the drawings is employed. In this construction the door will be given a substantial support from below and will also be prevented from becoming disengaged by reason of an upward draft in case of fire, the shoulder, being formed at right angles, preventing an upward displacement. In case it is desired to merely support the doors the construction as shown in Fig. 7 of the drawings is employed.
- 5 10 The inclined shoulder of the latter will permit it to be easily raised, as will be obviously apparent.
- I call attention to the fact that only two doors above and below the elevator-car have 15 been shown and described; yet any number of doors may be easily arranged to operate in the same manner, a corresponding number of additional lines and weights being necessary to accomplish the operation.
- 20 Another advantage gained by the novel arrangement of the weights resides in the fact that each door arranged beneath the elevator-car is operated by a single counterbalance-weight. Heretofore four weights have been 25 employed to accomplish this purpose. The four lines being attached to each weight and operating in unison will effectually prevent the doors from binding in the elevator-shaft as the car ascends and descends.
- 30 It will be noted that various changes may be made in the details of construction of the above-described device without departing from the general spirit of my invention.
- Having fully described my invention, what 35 I claim as new, and desire to secure by Letters Patent, is—
1. In an elevator, a car, an operating-rope, a series of doors arranged above the car, a series of pivoted spring-pressed arms and links 40 arranged on the lower door, bolts operated by the arms and the operating-lever connected

with the arms, as and for the purpose described.

2. In an elevator, a car, an operating-rope, a series of doors arranged above said car, a series of pivoted spring-pressed arms and links 45 arranged on the lowermost door, bolts operated by the arms, a notched gravity-lever, and an operating-lever connected with the arms, as and for the purpose described. 50

3. In an elevator, the combination of a car, a series of doors, spring-pressed arms carried by one of the doors, and a gravity-pawl having inclined bearing-surfaces, a weighted extremity and a notch as and for the purpose 55 described.

4. In an elevator, a car, a series of doors arranged to be operated by the car, a pulley, a line arranged on the lowermost door above the car, an operating-lever, arms having link 60 connections with the lever, and bolts operated by the lever, as and for the purpose described.

5. In an elevator, a car, a series of doors arranged to be operated by the car, a pulley, a line arranged on the lowermost door above 65 the car, an operating-lever, arms having link connections with the lever, bolts operated by the lever and gravity-pawls having inclined surfaces, weighted extremities, and notches, as and for the purpose described. 70

6. In an elevator, a series of doors arranged in the shaft, a series of weights adapted to travel in vertical alinement, each door having a single weight, and connections between each door and its weight, as and for the purpose 75 described.

In testimony whereof I affix my signature in presence of two witnesses.

ROBERT W. HARE.
